CLAIM

The ornamental design for a wall mounted support rack for headband, barrette, and bow wearing apparel, as shown and described.

DESCRIPTION

FIG. 1 is a top, front, and left side perspective view of a wall-mounted support rack for headband, barrette and bow wearing apparel showing my unique design;
FIG. 2 is a front elevational view thereof;
FIG. 3 is a right side elevation view thereof, the left side elevational view being a mirror image thereof;
FIG. 4 is a bottom plan view thereof;
FIG. 5 is a top plan view thereof; and,
FIG. 6 is a rear elevational view thereof.

FIG. -1-

FIG. -2-

FIG. -3-

FIG. -4-

FIG. -5-

FIG. -6-
